UNITED STATES PATENT OFFICE.

JOHN J. LONG, OF NORFOLK, VIRGINIA.

REVERSIBLE CUFF.

1,396,643.

Specification of Letters Patent. Patented Nov. 8, 1921.

Application filed April 4, 1921. Serial No. 458,491.

To all whom it may concern:

Be it known that I, JOHN J. LONG, a citizen of the United States, residing at Norfolk, in the county of Norfolk and State of 5 Virginia, have invented new and useful Improvements in Reversible Cuffs, of which the following is a specification.

This invention relates to an improvement in reversible cuffs, and more particularly 10 to the means for securing the cuff to the garment sleeve.

It is an object of this invention to provide a cuff of ordinary construction, such as the fold-over type, which may be reversed without detaching the same from the sleeve.

Another object of the invention is the provision of means for securing the cuff to the sleeve of such a character as will permit the reversal of the cuff without detachment 20 from the sleeve, and by a turning movement about an axis extending lengthwise of the sleeve.

It is well known in the art to provide detachable cuffs, but it has been found in the 25 trade that a cuff which is permanently attached to the garment sleeve is preferred, generally, to the detachable type of cuff. As is well known, due to the fact that the cuff becomes soiled long before the remainder of the garment, it is highly desirable 30 that the cuff be reversible. Heretofore, so far as I am aware, cuff constructions have been devised which, when permanently attached to the sleeve, are reversible only by 35 a turning or folding movement about an axis extending across or transversely of the sleeve. This construction is objectionable due to the fact that it necessitates the provision of a plurality of plies, making the cuff thick, and, therefore, objectionable, particularly in warm weather.

The present invention accomplishes the foregoing objects by securing the cuff to the sleeve permanently at but a single point, 45 preferably at a substantially central point along the rear edge of the cuff. On each side of this point the cuff is detachably secured to the sleeve so that when it is desired to reverse the cuff it may be detached 50 from the sleeve at all but its point of perma-

nent attachment, and then reversed by a turning movement about an axis extending lengthwise of the sleeve.

In the accompanying drawings there is shown one embodiment of the invention, 55 and from the following detailed description the above objects of the invention, together with other objects of a more minute character, will become more clear.

In the drawings:—

Figure 1 is an elevational view of the inside of a cuff showing the same partially in position to be folded over for wearing,

Fig. 2 is a view similar to Fig. 1 showing the outer ply of the cuff folded back over 65 the inner ply,

Fig. 3 is a detailed view of a portion of the cuff taken from the outside of the same,

Fig. 4 is a view similar to Fig. 1 showing the cuff at an intermediate stage during the 70 reversal of the same, and

Fig. 5 shows the cuff entirely reversed and ready to be secured for wearing.

Referring to the drawings for a more detailed description, 10 indicates the sleeve 75 of a garment which may have the usual cuff band 11 at its open divided end, the cuff band having free ends 12 provided with any suitable securing means, such as the buttonholes 13. 14 indicates a cuff of any 80 ordinary construction, in the present instance being a cuff of the fold-over type, having an outer ply 15 and an inner ply 16 when folded over. At a suitable point, which may be located substantially centrally 85 along the rear edge of its inner ply, the cuff is secured to the band 11 by means of a tab 16. This tab is shown in the present instance as being formed upon the cuff by means of converging incisions or slits 17 90 extending a short distance into the cuff from its rear edge. The tab, thus formed integral with the cuff, is secured to the cuff band, preferably permanently, as by means of a line of stitching 18.

At each side of the tab the cuff is detachable from the sleeve; any suitable means may be provided for detachably securing the cuff to the sleeve, such as buttonholes 19 95 formed in the cuff and registering with the 100

buttonholes 13 in the cuff band, a button 20 passing through the registering holes.

As shown in Fig. 2, the cuff is in condition to be worn, it being necessary only to close the same by passing the usual cuff link through the buttonholes 21. When it is desired to reverse the cuff the same is detached from the sleeve at each end and unfolded to the position shown in Fig. 3. The cuff is then turned about an axis extending lengthwise of the sleeve, the center of turning movement being the tab 16. Obviously, as the cuff is turned the tab is twisted, as shown in Fig. 4, and the cuff is brought to the position shown in Fig. 5. Preferably, when the cuff is reversed, one portion 23 of the inner ply on one side of the tab is placed upon the exterior of the cuff band, while the other portion 24 on the opposite side of the tab is placed either on the exterior or, as shown, upon the interior of the cuff. The cuff may then be secured at each free end, as shown in Fig. 2, by means of the buttons 20 and the outer ply folded back, as in Fig. 5. Due to the fact that the tab 16 is extremely narrow, the twisting of the same does not form an appreciable lump, and after a short period of wearing this twisted tab is materially flattened.

It should be understood that the invention is not limited to the specific details of construction described and shown, material modifications being possible while still retaining the essential features of the invention, which are more clearly defined in the following claims.

I claim:

1. The combination of a garment sleeve and a cuff for said sleeve having substantially centrally along one edge a plurality of spaced slits forming a tab, said tab being secured to the sleeve and permitting a reversal of the cuff by turning the same about an axis extending lengthwise of the sleeve without breaking said connection between the cuff and the sleeve.

2. A garment sleeve, a cuff for said sleeve, and means for permanently securing the cuff to the sleeve permitting a reversal of the cuff by turning the same about an axis extending lengthwise of the sleeve without breaking said connection between the cuff and the sleeve.

55 3. A garment sleeve having a cuff permanently secured thereto at a single intermediate point, said cuff being detachable from the sleeve at each side of said intermediate point and being reversible by turning about said point on an axis extending lengthwise of the sleeve.

4. A garment sleeve having a cuff permanently secured thereto at a single intermediate point along the end of the sleeve, 60 said cuff being detachable from the sleeve

at each side of said intermediate point and being reversible by turning about said point on an axis extending lengthwise of the sleeve.

5. A garment sleeve having a cuff permanently secured thereto at substantially a central point along the cuff, said cuff being detachable from the sleeve on each side of said point of attachment and being reversible by turning about said point and about an axis extending lengthwise of the sleeve. 70 75

6. A garment sleeve having a cuff permanently secured thereto at substantially a central point along the rear edge of the cuff, said cuff being detachable from the sleeve on each side of said point of attachment and being reversible by turning about said point and about an axis extending lengthwise of the sleeve. 80

7. A garment sleeve having a cuff permanently secured thereto at a single point located at substantially the central portion of the cuff along its rear edge, means for detachably securing the cuff to the sleeve on each side of said central portion, said cuff being reversible by turning about said central portion and about an axis extending lengthwise of the sleeve. 85 90

8. A garment sleeve, a cuff for said sleeve, a tab permanently securing together the cuff 95 and sleeve at an intermediate point on the cuff, said cuff being detachable from the sleeve on each side of the tab and being reversible by turning about said tab as a center and twisting the tab.

9. A garment sleeve, a cuff for said sleeve, a tab on the cuff at substantially a central point along its rear edge, said tab permanently securing together the cuff and the sleeve, and means for detachably securing 105 the cuff to the sleeve on each side of said tab, the cuff being reversible by turning the same and twisting the tab. 100

10. The combination of a garment sleeve and a cuff for said sleeve having along one 110 edge at substantially a medial point a partially cut-away portion forming a tab, said tab being secured to the sleeve and permitting a reversal of the cuff by turning the same about an axis extending lengthwise of the sleeve without breaking the connection between the cuff and the sleeve. 115

11. A cuff having substantially centrally along one edge a plurality of spaced slits forming a tab adapted to be secured to a 120 garment sleeve and permitting a reversal of the cuff by turning the same about an axis extending lengthwise of the sleeve without breaking the connection between the cuff and the sleeve.

12. A cuff having along one edge at substantially a medial point a partially cut-away portion forming a tab adapted to be secured to a garment sleeve and permitting a reversal of the cuff by turning the same 130

about an axis extending lengthwise of the sleeve without breaking the connection between the cuff and the sleeve.

13. A cuff having along one edge at substantially a medial point a partially cut-away portion forming a tab adapted to be secured to a garment sleeve and permitting a reversal of the cuff by turning the same

about an axis extending lengthwise of the sleeve without breaking the connection between the cuff and the sleeve, said tab not extending beyond the edge of the cuff. 10

In testimony whereof I have hereunto set my hand.

JOHN J. LONG.
